No. 1,219.

George W. Smith's design for an improving pitcher

Patented April 3, 1880.

George W. Smith
Inventor

Des. 1219

George W. Smith, of Hartford, Conn.
Letters Patent No. 1219, dated April 3, 1860.

The schedule referred to in these Letters Patent and making part of the same.

To all whom it may concern:

Be it known that I, George W. Smith, of Hartford in the County of Hartford and State of Connecticut, have invented or produced a new and original Design for an Ice Refrigerating Pitcher, and I do hereby declare that the following is a full, clear and exact description of the same, reference being had to the annexed drawings, making a part of this Specification, in which -

Figure 1, is an elevation of a pitcher showing my design.

Figure 2, a horizontal section of ditto, taken in the line xx, figure 1.

Similar letters of reference indicate corresponding parts in the two figures.

In figure 1, the elongated egg-shaped projections *a*, are clearly shown. These projections extend nearly the whole height of the body of the pitcher, and they have a gentle swell or protuberance as shown clearly in figure 2. - The projections *a*, extend entirely around the pitcher side by side, but they are not in direct contact as each projection *a*, is nearly encompassed by a rounded bead *b*, said beads terminating a short distance from the centers of the upper and lower ends of the projections *a*, as shown clearly in figure 1. The beads *b*, are

2

Dec. 12/9

transversely of about semi-circular form as shown clearly in figure 2, and they are in contact between the projections a, as shown clearly in figure 1.

The base c of the pitcher, as well as its upper part d, including the nozzle e, may be of any suitable form as they comprise no part of the design.

I claim as new and desire to secure by Letters Patent.

The configuration of the projections a, and beads b, as shown to form a new and original design for an ice or refrigerating pitcher.
